DESIGN FOR A TEXTILE FABRIC OR SIMILAR ARTICLE

Nicholas L. Wershing, New York, N. Y.

Application September 19, 1938, Serial No. 79,985

Term of patent 3½ years

To all whom it may concern:

Be it known that I, Nicholas L. Wershing, a subject of the King of Rumania, residing in the city of New York, county of New York, and State of New York, have invented a new, original, and ornamental Design for a Textile Fabric or Similar Article, of which the following is a specification, reference being had to the accompanying drawing, forming a part thereof.

The figure is a plan view of a textile fabric showing my new design.

The design consists of a series of alternate rows of dull and lustrous horizontal stripes, each dull stripe being corded, the lustrous stripes being crimped and having a bead-like appearance, as shown.

I claim:

The ornamental design for a textile fabric or similar article, as shown and described.

NICHOLAS L. WERSHING.
